UNITED STATES PATENT OFFICE.

EDWARD H. WALTERS, OF CHICAGO, ILLINOIS, ASSIGNOR TO LITE PRODUCTS CORPORATION, OF CHICAGO, ILLINOIS, A CORPORATION OF DELAWARE.

WINDOW-SASH FASTENER.

Application filed September 14, 1921. Serial No. 500,473.

To all whom it may concern:

Be it known that I, EDWARD H. WALTERS, a citizen of the United States, residing at Chicago, in the county of Cook and State of Illinois, have invented a certain new and useful Improvement in Window-Sash Fasteners, of which the following is a specification.

My invention relates to window sash fasteners, and while useful in various places and for various structures, it is particularly useful for automobile tops where a quick-operating window and ventilator is desirable. In my device a pane of glass is vertically slidable in a frame, and the object of the invention is to provide simple and largely automatic means for supporting the pane at any desired elevation.

I accomplish this object by the mechanism illustrated in the accompanying drawings in which—

Figure 1 is a view from the inside of the window showing the vertically movable pane in partially raised position.

Figure 2 is an edge view of the structure looking toward the right in Figure 1.

Figure 3 is a plan sectional detail on the line 3—3 Figure 1 and

Figure 4 is a perspective view showing the operating mechanism on an increased scale.

Like numerals denote like parts throughout the several views.

In the form selected to illustrate the invention there is a frame composed preferably of metal and formed in two parts 1 and 2. For convenience I will refer to these as the inner and outer frame members respectively. In practice they are held together by screws 4 or other appropriate means. In order to assist the screws in preventing the frame members 1, 2 from slipping relatively to each other, their contacting surfaces have diamond knurling 3.

In the upper part of the frame is a fixed pane 5. The inner frame member is rabbed to accommodate it, and the pane rests upon a shoulder 6 at the lower end of the rabbets, as best shown in Figure 1. The inner frame has vertical grooves 8 which

form guides for the vertically movable pane 9. The parts are so arranged that the movable pane slides in a plane parallel and adjacent to the fixed pane. It is not essential that the upper pane be the fixed one and the lower pane the slidable one, but the parts are here illustrated in this manner and will be so described to avoid confusion.

I usually employ heavy panes of glass in order that they may possess sufficient strength without reinforcing borders. When I thus employ thick glass it is possible and desirable to form a recess 12 in it to accommodate the fingers of the operator and make it easy for the pane to be raised or lowered.

Mounted on the frame at the side of the movable pane are two arms 15. These are held seated by pivot pins 16 having heads 17 at the outer end and smaller heads 18 counter-sunk in the back side of the frame member 1, as best shown in Figure 3. At the free end of each arm is a handle 20 by which it may be rotated and a contactor 21 for engaging the slidable pane. The material best suited for the purpose is rubber. The arms bear upon bearing surfaces 22 formed on the frame and slanting toward the surface of the slidable pane, as best shown in Figure 3. The result is that when an arm is in an upstanding position and starts to swing downward and inward over the pane, the contactor 21 not only swings downward and inward, but also moves directly toward the pane itself, the consequence being that finally the pressure of the contactor against the pane will be sufficient to produce enough frictional engagement between the pane and the frame to support the pane. In other words, the movement of the arm in swinging downward from upstanding to horizontal position has one component which is normal to the surface of the pane, and the result will be that the contactor will be pressed so tightly against the pane as to support it in the frame.

A lug 25 is formed on the surface of the inner frame member 1 in such position as to prevent the arm from descending below the horizontal position, as best shown in Figures 1 and 4. Thus the lug acts as a stop

for limiting the downward movement of the arm below horizontal position, at which position the pressure of the contactor upon the pane is maximum.

5 The operation will now be readily understood. Let it be assumed that the parts are in the positions shown in full lines in Figures 1, 3 and 4, in which case the arms 15 are in horizontal position and the pressure of the contactors 21 is great enough to securely hold the slideable pane at the elevation to which it happens to be adjusted. If, now, the operator wishes to adjust the pane to a higher position all that is necessary is to 10 push upward on the pane. The frictional engagement of the rubber contactors on the pane will cause the arms to swing upward and this simultaneously moves the contactors away from the surface of the pane. 15 The pane thereupon becomes freely slideable. When the pane has been raised somewhat above the new elevation desired the operator permits it to move slightly downward, whereupon the action of gravity on the arms 20 augmented by the friction of the contactors upon the surface of the pane will cause the arms immediately to swing downward and reengage the pane and hold it at the new desired elevation. It will be evident from 25 this that the action is automatic in the sense that the pane is automatically released and that the new level will be automatically maintained. The device also has the advantage of avoiding the need of perforating or 30 notching the pane. The contactors tend at all times to engage the pane, and hence they will "take hold" at any and all points. It may be said that the pane is thus adjustable by differential increments. If, now, the operator wishes to lower the pane, he will first 35 raise it sufficiently to release the contactors and then swing the arms to vertical position, as shown in Figure 2 and in dotted lines in Figure 4. In this position there is no tendency for the arms to engage the glass, and hence the pane may be raised or lowered freely.

It will be evident that the device is simple and has little tendency to get out of order. 50 It has another advantage especially for moving vehicles, in that it tends to prevent rattling of the pane in the frame. The pane may be loose in its guides or rabbets at the sides of the frame, but as soon as the clamping arms 15 are lowered they will press the contactors firmly against the pane and prevent the latter from vibrating.

Having thus described my invention what I claim as new and desire to secure by Letters Patent is:

1. A window having a frame, a pane slideable therein, an arm pivoted to the frame upon an axis oblique to the plane of the pane, whereby rotation about its axis will 65 bring the free end of the arm toward and

from the surface of the pane, the plane of rotation of the arm being near enough to the plane of the pane to cause the free end of the arm to exert pressure upon the pane substantially normal to its surface when said arm is rotated to acting position.

2. A window having a frame, a pane slideable therein, an arm having a contactor adapted to frictionally engage said pane, and also to exert pressure on it normal to its surface, and a pivot for pivotally securing the arm to the frame, the frame having a bearing surface for the arm which is oblique to the surface of the pane whereby rotation of the arm will produce a movement of the contactor having a component normal to the surface of the pane, to thus cause said contactor to move toward and away from the pane as the arm is rotated.

3. A window having a frame, a pane slideable in the frame, an arm pivoted to the frame upon an axis slightly inclined from a line normal to the plane of the pane whereby rotation about its axis will bring the free end of the arm toward and from the surface of the pane, a contactor mounted on the arm remote from the axis thereof and adapted to frictionally engage the pane whereby a sliding movement of the pane in one direction will cause the arm to increase the pressure of the contactor on the pane and a sliding movement of the pane in the opposite direction will cause the arm to decrease the pressure of the contactor upon the pane, the axis of the arm being so positioned that a downward movement of the free end of the arm from an approximately upstanding position to an approximately horizontal position will move the contactor toward the pane, thereby causing gravity to assist the arm in moving the contactor toward the pane.

4. A window having a frame arranged substantially vertically, a pane slideable vertically in the frame, an arm pivoted to the frame and extending part way across the pane, a contactor carried at the free end of the arm and adapted to frictionally engage the pane, the frame having a bearing surface disposed at an angle to the surface of the pane in such manner that the downward swing of the arm from an upstanding position will move the contactor not only downward but also toward the pane to clamp it in the frame, the contactor and arm being close enough to the pane to cause the contactor to engage the pane with sufficient pressure to be actuated by the latter before the arm reaches horizontal position, whereby further downward movement of the pane will automatically increase the pressure of the contactor upon it.

5. In combination, a window frame, a pane slideable vertically in said frame, an arm pivoted to the frame and extending part

way across the pane, a contactor carried at the free end of the arm and adapted to frictionally engage the pane, the frame having a bearing surface disposed at an angle 5 to the surface of the pane in such manner that the downward swing of the arm from an upstanding position will move the contactor not only downward but also toward the pane to clamp it in the frame, and means for limiting the downward swing of the 10 arm.

In witness whereof, I have hereunto subscribed my name.

EDWARD H. WALTERS.
